UNITED STATES PATENT OFFICE.

GEORGE HILL, OF LEDBURY, ENGLAND.

SPRING-CLASP.

SPECIFICATION forming part of Letters Patent No. 610,967, dated September 20, 1898.

Application filed September 23, 1897. Serial No. 652,710. (No model.)

To all whom it may concern:

Be it known that I, GEORGE HILL, a subject of the Queen of Great Britain, and a resident of Ledbury, in the county of Hereford, England, have invented certain new and useful Improvements in Clips, of which the following is a full, clear, and exact specification.

This invention consists of a new or improved clip for connecting articles together and also for use as what is known as a "trousers-clip."

In order that my invention may be fully understood, I will now refer to the annexed drawings, in which—

Figure 1 is a perspective view of my improved clip in its open position, and Fig. 2 a perspective view of same when in its closed position.

a is a piece of elastic material which is bent approximately to the shape of the letter **N**, the ends *b* of which are serrated, as shown.

c is a support attached to one of the limbs of the clip and which carries the locking-piece *d*, which is pivoted to the support *c* at *e*. When the locking-piece *d* is moved in the

direction of the arrow 1, the prolongation *f* 25 will cause the serrated ends *b* and bent parts *g* to approach one another and so clip or hold the required substances or articles, such as cloth, which may be placed between the serrated ends *b* and bent parts *g*. 30

Having thus described my invention, what I claim, and desire to secure by Letters Patent, is—

A clip consisting of a piece of elastic material bent approximately to an **N** shape; a support attached to one of the limbs; a pivoted locking-piece carried by said support and having a prolongation for the purpose of bringing the clipping ends together when the locking-piece is operated, substantially as 35 described and illustrated herein. 40

In testimony that I claim the foregoing I have hereunto set my hand this 6th day of August, 1897.

GEORGE HILL.

Witnesses:

W. I. WEEKS,
PERCY R. SOLDREIN.
